UNITED STATES PATENT OFFICE.

CLEMENT L. V. MUNDHENK, OF MARION, INDIANA.

TIRE-BOLT-WRENCH MACHINE.

SPECIFICATION forming part of Letters Patent No. 790,587, dated May 23, 1905.

Application filed June 14, 1902. Serial No. 111,661.

To all whom it may concern:

Be it known that I, CLEMENT L. V. MUNDHENK, a citizen of the United States, residing at Marion, in the county of Grant and State of Indiana, have invented certain new and useful Improvements in Tire-Bolt-Wrench Machines; and I do declare the following to be a full, clear, and exact description of the invention, such as will enable others skilled in the art to which it appertains to make and use the same, reference being had to the accompanying drawings, and to letters of reference marked thereon, which form a part of this specification.

15 Figure 1 is a view in perspective of the machine secured to a stationary back support. Fig. 2 is a vertical sectional view of Fig. 1. Fig. 3 is a side view of eccentric, lever-yoke, and a jaw of cutting device. Fig. 4 is a view in perspective of wrench socket and shaft.

This invention has relation to wrenches for removing tops from bolts of tire-wheels; and it consists in the novel construction and combination of parts, as hereinafter set forth.

25 In the annexed drawings, illustrating this invention, A is a metal frame cast in one piece having a back vertical supporting-plate m , with side projections α at the top and bottom, with slotted openings for the purpose of securing the frame rigidly to a suitable object for use, a pair of jaws for the pivoting-lever extending outward from the face of the back plate m at the top, joined to said back plate m below said jaws, a top plate m' extending outward, having near its center suitable openings f to receive and support a vertical bevel-gear wrench-shaft C, said plate m' being joined at its outer extremity to a face-plate m^3 , which projects at right angles downward. Upon the

40 upper end of said front frame-plate is a fixed jaw d, adjustable by means of a set-screw, said front plate having at convenient points means of attaching and supporting the bevel-gear shaft and lever B. Extending outward from the lower end of said back plate m to the lower end of said front plate m^3 is a bottom plate m^4 , forming a union at right angles with said front plate. Extending outward from the back plate at a point a little below the top plate m' 45 is a plate m^2 , parallel with said top plate, but

extending only part way, said plate having near its extremity a suitable shaft-opening k , corresponding to and with the one, f , described near the center of the top plate and for the same purpose and joined at its outer extremity with a vertical plate m^5 at right angles downward and parallel with the front end plate to a point of union with the bottom plate, said vertical plate being provided with a shaft-opening b , corresponding with the front plate-opening, the whole comprising a framework for the uses and purposes herein-after described.

Referring to Fig. 1, B is a metal cast lever having at its upper end a jaw d, provided with a cutting-blade h, inserted in an opening upon its front face corresponding to the fixed jaw d and cutting-blade, as described as a part of the front frame-plate m^3 , said lever being provided at its lower extremity with a yoke V, as shown in Fig. 3, constructed to engage an eccentric located upon a shaft, hereinafter described, operating in conjunction with said lever, said lever having at a convenient point a suitable opening for pivoting and operating in conjunction with eccentric-shaft to be described, producing a cutting device for removing the projecting end of a bolt. D is a short metal cast link-lever having a pivoted end upon one end engaging the jaws upon the face-plate heretofore described, said link-lever having at a point on its under side and directly over the center of wrench-socket, Fig. 4, hereinafter described, a dog j, at its other end a round bearing-pin engaging a lever E, operating in conjunction therewith.

In Fig. 1, E is a metal cast lever having a slightly-curved handle end and downward and inward curved hook l to engage the felly of a wheel to form a fulcrum, said lever having at a convenient point a slotted opening extending through said lever in a plane with the round end of the short link-lever last described suitable to engage the round bearing end of said short link-lever and permitting the adjustment of said curved lever-hook to different points on a felly when the machine is in use.

Fig. 4 is a hollow shaft having at one end a wrench-socket to be used as a wrench, having

an opening on one side through which the disengaged nut may be discharged, the said shaft adapted to engage with and be operated by a train of bevel-gears working in a vertical plane 5 fastened to a shaft and supported by the shaft passing through the frame-plates at convenient points below the top plate. Said shaft has as a part of its construction an eccentric conveniently located to engage a yoke V, Fig. 10 3, on a lever heretofore described, and a crank at right angles to a line of its location in the frame, Figs. 1 and 2. A bevel-gear engages the above-described gear, working in a horizontal plane at a point between the top plate 15 and the one described as below it, Fig. 2.

I am aware that tire-bolt machines have been made with vertical and horizontal bevel-gear and shafts operating in conjunction with a nut-wrench. I therefore do not claim such a combination broadly; but

What I do claim as my invention, and desire to secure by Letters Patent, is—

In a tire-bolt-wrench machine the combination of a vertical metal cast frame A, having 25 vertical and horizontal plates, a cutting-jaw upon the front face-plate, suitable openings

in plates to receive and support a bevel-gear and shaft, a short metal link-lever pivoted to the jaws in the back frame-plate, said lever having a dog and round bearing end to engage 30 with metal cast hand-lever E through a longitudinal slotted hole, said lever having a handle end and a curved hook end to engage with the felly of a wheel in use, a square socket-wrench with side opening and shaft, a lever 35 having a pivotal center with a cutting-jaw upon its upper end to engage with a corresponding fixed cutting-jaw and a yoke upon its lower end to engage with a shaft having an eccentric thereon, said shaft provided with 40 a bevel gear-wheel engaging with a wrench-socket-shaft gear-wheel, said shaft operated by means of a crank and handle, substantially as specified.

In testimony whereof I have signed my name 45 to this specification in the presence of two subscribing witnesses.

CLEMENT L. V. MUNDHENK.
